UNITED STATES PATENT OFFICE.

JOHN F. JACKSON, OF HOUGHTON, MICHIGAN.

DAM.

No. 902,733.

Specification of Letters Patent.

Patented Nov. 3, 1908.

Application filed July 11, 1908. Serial No. 443,122.

To all whom it may concern:

Be it known that I, JOHN F. JACKSON, a citizen of the United States, residing at Houghton, in the county of Houghton and State of Michigan, have invented new and useful Improvements in Dams, of which the following is a specification.

The invention relates to dams, and in most of its features more especially to dams which 10 constitute a unitary structure, as for instance reinforced concrete dams.

Objects of the invention are to produce a dam which possesses extraordinary stability while requiring a relatively small amount of 15 material and being of low cost of construction; to provide a dam wherein great vertical hydrostatic pressure upon the dam structure may be secured and used against the horizontal hydrostatic pressure to give great stability 20 to the dam.

A further object of the invention is to produce such a structure which, while meeting all the requirements of service will have an attractive appearance such as is produced in 25 the best practice with masonry dams.

These and other objects of invention will in part be obvious and will in part more fully appear hereinafter.

The invention consists in the novel constructions, arrangements, combinations, 30 methods and improvements herein shown and described.

The accompanying drawings, referred to herein and forming a part hereof, illustrate 35 one embodiment of the invention, the same serving in connection with the description herein to explain the principles of the invention.

Of the drawings: Figure 1 is a vertical section through a dam structure; Fig. 2 is a fragmentary elevation looking to the left referred 40 to Fig. 1; Figs. 3 and 4 are fragmentary horizontal sections on the lines A—A and B—B, respectively, of Fig. 1; and Figs. 5 and 6 are 45 diagrammatic views serving to illustrate certain principles of the invention.

In carrying out my invention I provide a 50 dam structure which is unitary, that is, a structure such that various loads or forces applied thereto may be caused to act in total along the line of a common resultant. I further provide such a structure having a wall or equivalent element to contain the water and it, of course, receives the horizontal hydrostatic load or pressure. As is well understood, for a given height of water this load is

fixed or constant. I provide further unitary with said wall or equivalent element a part or structure extending beneath the contained water to receive a vertical hydrostatic 60 load or pressure. Furthermore, I vary the form and extent of such part to secure as great a vertical hydrostatic load as I may desire in connection with the particular structure. 65

By reason of the dam being a unitary structure I then utilize this vertical hydrostatic load to render the dam stable against the pressure or strain of the horizontal hydrostatic load. That is, I produce acting upon 70 this unitary structure, a resultant of large magnitude and, owing to the large vertical component, said resultant makes a large angle with the horizontal or common level. I may also shape and arrange the structure 75 so that said resultant will cut the vertical upon which the center of gravity of the dam structure lies and may also cause the line of action of the resultant to pass very near to the center of gravity of said structure. 80 This renders possible a maximum of strength and stability in the structure with a minimum of material, as will be now understood by those skilled in the art, as well as realizing the other objects of invention which I 85 desire to attain.

Referring to the accompanying drawings, illustrating by way of example one embodiment of the invention and one manner of carrying out the method, 1 indicates a wall 90 for supporting the horizontal load of the hydrostatic pressure. A part 2 of the dam structure is shown extending upstream, that is, beneath the contained water to receive a vertical load from the hydrostatic pressure 95 as hereinabove set forth. This part may for convenience be styled the foot of the dam. The wall 1 is shown supported upon the foot 2 and means are provided for connecting the wall and the foot into a unitary structure. 100 This may be done by means of reinforcing elements and this may very conveniently be done when the dam is of concrete. Such a construction is shown in the illustrated embodiment. Reinforcing elements or members 3 are shown in said foot 2. The arrangement and interrelation of said members need not be set forth herein in detail, but it will be understood that these elements will be arranged in accordance with sound practice so as to give the foot 2 adequate strength 110 to successfully bear the various strains to

be put upon it. Suitable reinforcing members 4 are also provided within the wall 1 which will be described more in detail hereinafter. The wall 1 is shown at 6 as inclined 5 in an upstream direction before joining the foot 2, although this particular arrangement is immaterial so far as concerns many features of the invention. Reinforcing members 7 are provided anchored in the foot 2 10 and in the wall 1 and may also be in tension therebetween for the purpose of rendering the wall and foot into a unitary structure. Said reinforcing members 7 may be anchored to the reinforcing members 3 and 4, respectively, 15 and are so shown in the drawings.

According to certain features of the invention supporting members 8 are provided for the wall 1, and such members are shown in the drawings on the downstream side of 20 the wall 1. Means for making these also a part of the unitary dam structure are contemplated by certain features of the invention. According to another feature thereof the foot 2, in this embodiment, is extended 25 downstream beyond the wall 1 and the supports 8 are carried upon said foot. The supports 8 are shown herein in the form of buttresses and, if desired, may be shaped generally similar to those used in the best masonry practice. Suitable reinforcing devices 30 may be used in the buttresses 8 and the form thereof herein shown comprises suitable metal bents 9 passing vertically and transversely through the buttresses and 35 may also pass downwardly through the parts of the wall 1 in alignment with the buttresses and are so shown herein, and also as extending into the foot 2. The reinforcing elements may be arranged in shear in the spans 40 of the wall 1 between the buttresses and certain of such elements are indicated by the numeral 10. Certain of the reinforcing elements may furthermore be in tension between the buttresses and the wall and certain 45 of such elements are indicated at 11 and elsewhere in the drawings. Certain of said reinforcing elements may also be in tension from the buttresses to the foot either directly or through the lower part of the 50 wall 1 and are accordingly likewise so shown at 12 and elsewhere in the drawings. It will be understood, however, that I do not limit myself to the details of arrangement of the reinforcing elements, my object being to provide a unitary structure embodying the 55 principles hereinbefore set forth and incidentally to meet all the loads and strains which act upon such a structure. Webs 13 may be provided between the buttresses 8 and a concrete strut 14 is also shown so located.

The parts of the structure, having especially in view the wall and the upstream portion of the foot, or the entire foot when only 60 the upstream portion is used, may be pro-

portioned and arranged so that the resultant of the horizontal and vertical components of the hydrostatic pressure will fall near the center of gravity of the dam structure and such an arrangement is substantially shown 70 in the diagram of Fig. 5, the resultant being indicated by 16 and the vertical line on which the center of gravity is located is indicated by 15. With such an arrangement also the resultant of the weight of the dam 75 and the above resultant will also fall in very nearly the same relation as shown at 17 in Fig. 6. It will be understood, however, that the invention in its broader aspects is not limited to such an arrangement or proportioning, nor to any particular arrangement or proportioning, or to any specific form of construction.

It will be understood from the foregoing that a dam structure has been provided 85 which realizes the objects of invention and advantages herein set forth, together with other objects and advantages, and which will serve to illustrate the principles of the invention.

What I do claim as my invention and desire to secure by Letters Patent, is:

1. A dam including in combination a confining portion which receives the horizontal load of the hydrostatic pressure, a submerged 95 portion for the purpose of taking a vertical hydrostatic pressure, and means uniting said two portions so that the vertical pressure upon the submerged portion is utilized to render the dam structure stable against the 100 action of the horizontal pressure, the submerged portion being of such extent and conformation as to secure a vertical hydrostatic pressure of such magnitude as to impart to the total resultant pressure upon the unitary 105 dam structure a magnitude and direction such as to give the desired degree of stability to the dam structure against the sliding and overturning tendency due to the horizontal hydrostatic pressure.

2. A dam structure including in combination a part for confining the water and a part extending beneath the water and intended to receive an additional vertical hydrostatic load, which load acts to increase the magnitude and vertical inclination of the total resultant hydrostatic pressure upon the dam structure thereby to give it greater stability against the sliding and overturning tendencies due to the horizontal hydrostatic pressure on the said confining part.

3. A dam including in combination a substantially vertical wall for supporting the horizontal load of the hydrostatic pressure, a substantially horizontal foot extending upstream to receive a vertical load from the hydrostatic pressure, and means uniting said wall and foot into a unitary structure.

4. A dam including in combination a wall for supporting the horizontal load of the hy-

drostatic pressure, a foot extending upstream to receive a vertical load from the hydrostatic pressure, reinforcing elements in said wall and in said foot, and tension members 5 connecting said reinforcing elements in the wall and foot respectively.

5. A dam including in combination a wall for supporting the horizontal load of the hydrostatic pressure, a foot extending upstream to receive a vertical load from the hydrostatic pressure, supporting members for said wall, and connections between said wall, foot and supporting members to render them into a unitary structure.

15. 6. A dam including in combination a wall for supporting the horizontal load of the hydrostatic pressure, a foot upon which said wall is supported, extending upstream and downstream from the wall, means for rendering said foot and wall into a unitary structure, and supporting members for said wall on the downstream side, said members being supported upon said foot.

7. A dam including in combination a wall 25 for supporting the horizontal load of the hydrostatic pressure, a foot upon which said wall is supported, extending upstream and downstream from the wall, means for rendering said foot and wall into a unitary structure, and supporting members for said wall 30 in compression on the downstream side, said members being supported upon said foot.

8. A dam including in combination a wall 35 for supporting the horizontal load of the hydrostatic pressure, a foot upon which said wall is supported, extending upstream and

downstream from the wall, supporting members for said wall in compression on the downstream side, said members being supported upon said foot, and reinforcing members 40 connecting said foot, wall and supporting members into a unitary structure.

9. A dam including in combination a wall for supporting the horizontal load of the hydrostatic pressure, a foot extending upstream 45 to receive a vertical load from the hydrostatic pressure, said parts being proportioned and arranged so that the resultant of the horizontal and vertical components of the hydrostatic pressure will fall near the center 50 of gravity of the dam structure, and means for connecting the wall and foot into a unitary structure.

10. A dam including in combination a wall for supporting the horizontal load of the hydrostatic pressure, a foot extending upstream 55 to receive a vertical load from the hydrostatic pressure, said parts being proportioned and arranged so that the combined resultant of the horizontal and vertical components of the hydrostatic pressure and the weight of the dam will fall near the center of 60 gravity of the dam structure, and means for connecting the wall and foot into a unitary structure.

In testimony whereof, I have signed my name to this specification, in the presence of two subscribing witnesses.

JOHN F. JACKSON.
